UNITED STATES PATENT OFFICE.

FRANK M. CAMPBELL AND ANTHONY C. DUNLEVY, OF ST. LOUIS, MISSOURI.

SKYLIGHT.

SPECIFICATION forming part of Letters Patent No. 244,711, dated July 19, 1881.

Application filed April 27, 1881. (No model.)

To all whom it may concern:

Be it known that we, FRANK M. CAMPBELL and ANTHONY C. DUNLEVY, of St. Louis, in the county of St. Louis and State of Missouri, 5 have invented new and useful Improvements in Skylights, of which the following is a description.

The object of this invention is to simplify the frame or sash structure of skylights, whereby 10 the same is rendered less expensive to manufacture, and more secure against rain, snow, dust, &c., from finding its way through the joints and under the caps or hoods covering the bars of the sash.

15 The invention is an improvement on a skylight patented to said Campbell the 6th day of November, 1877.

For illustrating the improved skylight reference will be had to the annexed drawings, making a part of this specification, in which—

20 Figure 1 is a vertical transverse section of the bars and glass of the improved skylight. Fig. 2 is a perspective view of a sash-bar.

Like letters of reference refer to like parts 25 in the several views.

That a full understanding of the nature and importance of the improvement over said patent may be had, a brief description of the patented sky-light alluded to will be made.

30 In the above said patented skylight each bar of the sash consisted of a single piece of sheet metal, so bent as to form a central web of the bar, and two gutters, one on each side of the web; also, two stiffening-flanges at the 35 lower edge of the web, one along each side thereof. The edges of the gutters served as supports for the plates of glass, which are laid thereon so that the edges may project over the gutters that the drippings from the glass 40 may fall therein. Over the edges of the plates of glass, and also over the bars, are placed caps or hoods drawn tightly down upon the glass by clamps. The longitudinal and transverse bars are made alike, and are connected 45 to each other by adjusting the parts of the one to the corresponding parts of the other, which are then united by soldering.

In practice it is found to be too much labor and requiring too much skill to make the bars 50 with two gutters and two stiffening-flanges and fit them together to form the sash; hence

the sash is expensive. It is also found that the rain and melting snow sometimes drifts in under the caps or hoods, and as it drips from the edge of the glass into the gutters more or less of it runs along back under the glass by 55 capillary attraction, and makes its way between the edge of the gutters and the glass, and falls therefrom to the inside of the building. To avoid these defects in the skylight the bars of 60 the improved skylight are made of a single piece of sheet metal, as in the former invention, as shown at A; but instead of making the bars with stiffening-flanges, they are made without them, retaining the two gutters B and C, one 65 on each side of the web D.

The plates of glass E are laid upon the edges of the gutters, as in the patented skylight, but not so close to the web. Over the edge or comb of the web is hung an apron, F, depending between the edges of the glass and the web, as seen in Fig. 1, and indicated by the dotted lines in Fig. 2. The sides of the apron depend and spread outward so far as to press against the 70 lower corner of the edge of the glass.

75 The apron may be kept distended, so as to be in contact with the glass by a spreader, which may consist of a rod, (not shown in the drawings,) extending along the under side of the apron near its line of contact with the 80 glass. Said rod should be attached to the side of the web by one or more springs, so adjusted that the resiliency of said springs will keep the apron in contact with the glass.

The apron may consist of rubber-cloth, tarred 85 paper, asbestos-cloth, or of felt, or other fibrous material, and may be kept in contact with the edges of the glass by the means before mentioned, or any suitable means, the elasticity of the material sufficing when it possesses that 90 quality. Felt is, however, preferred, as its loose fibrous quality will enable it to absorb the water more readily than may drip from the glass, and conduct it therefrom into the gutters by capillary attraction and gravity, instead of 95 passing along the under side of the glass and dripping into the space below.

Over the edges of the plates of glass and the apron are placed caps or hoods G, the edges of which rest upon the glass, and are secured in place with clamps H, substantially in the same manner as shown in the patent of Novem-

ber 6, 1877, above referred to. The space below the cap is filled with a packing of some fibrous or flocculent material, as shown in the drawings at N.

5 From the above it will be obvious that in constructing the bars of the sash without stiffening-flanges, they are consequently more simple in structure, and therefore can be made with less labor, skill, and of less material, 10 hence they are less expensive; and, furthermore, by virtue of the simple form of the bars the longitudinal and transverse bars can be more easily and readily adjusted to and joined to each other than when the said bars are made 15 with stiffening-flanges, and are equally secure and sufficiently strong.

The effect of the apron above described, by its contact with the edge of the glass, prevents the water that may find its way in under the 20 hood from flowing back by capillary attraction along the under side of the glass, diverts it downward into the gutters, and prevents it from leaking into the building, as aforesaid.

What we claim as our invention, and desire 25 to secure by Letters Patent, is—

1. In combination with the sash-bar, consisting of one piece of sheet metal and provided with gutters B and C, central compact web, cap G, packing inserted in the space be-

low the cap, and an apron hung upon the ridge 30 of the web of the sash-bar and depending therefrom between the said web and edges of the plates of glass, and means, as set forth, to keep said apron in contact therewith, substantially as set forth, and for the purpose specified. 35

2. In sash-structures for skylights, an apron of fibrous material, asbestos or rubber cloth, or its equivalent, arranged to depend from the ridge of the web of the sash-bar, and in contact with the edges of the glass, with the depending sides of said apron extending below 40 the glass into the gutters, substantially as described, and for the purpose set forth.

3. In skylights, the gutters B and C, with a web extending lengthwise through the said 45 gutters, with the glass plates on the sides thereof resting upon the edges of the gutters, in combination with an apron, F, arranged between the edges of said glass within the gutters, substantially as described, and for the purpose 50 set forth.

In testimony whereof we affix our signatures in presence of two witnesses.

FRANK M. CAMPBELL.
A. C. DUNLEVY.
